UNITED STATES PATENT OFFICE.

JAMES E. PRICE, OF PUEBLO, COLORADO.

DESIGN FOR A FOB.

47,145.

Specification for Design.

Patented Mar. 23, 1915.

Application filed January 27, 1914. Serial No. 814,829. Term of patent 3½ years.

To all whom it may concern:

Be it known that I, JAMES E. PRICE, a citizen of the United States, residing at Pueblo, in the county of Pueblo and State of Colorado, have invented a new, original, and ornamental Design for Fobs, of which the following is a specification, reference being had to the accompanying drawing, forming a part thereof.

The figure is a perspective view of a fob, showing my new design.

I claim:

The ornamental design for a fob, as shown.

JAMES E. PRICE.

Witnesses:

B. F. BALDWIN,
ALFRED WINTERS.
